his Attorney.*

UNITED STATES PATENT OFFICE.

CARL O. ANDERSON, OF BROOKLYN, NEW YORK.

DESIGN FOR A COTTER-PIN PULLER.

58,453.

Specification for Design.

Patented July 26, 1921.

Application filed March 5, 1921. Serial No. 450,110. Term of patent 7 years.

To all whom it may concern:

Be it known that I, CARL O. ANDERSON, a citizen of the United States, residing at New York, borough of Brooklyn, in the county of Kings and State of New York, have invented a new, original, and ornamental Design for Cotter-Pin Pullers, of which the following is a specification, reference being had to the accompanying drawing, forming part thereof, wherein—The figure is a perspective view of a cotter pin puller, showing my new design.

I claim:

The ornamental design for a cotter pin puller as shown.

Signed at New York, borough of Manhattan, in the county of New York and State of New York, this 2nd day of March, 1921, before two subscribing witnesses.

CARL O. ANDERSON.

Witnesses:

WILBUR C. ABBOTT,
WILBUR M. STONE.
